UNITED STATES PATENT OFFICE.

PAUL BUNIN, OF NEW YORK, N. Y.

VALVE-FITTING FOR SODA-WATER APPARATUS.

934,037.

Specification of Letters Patent. Patented Sept. 14, 1909.

Application filed August 4, 1908. Serial No. 446,886.

To all whom it may concern:

Be it known that I, PAUL BUNIN, a subject of the Czar of Russia, residing in the borough of Manhattan, New York city, county 5 and State of New York, have invented certain new and useful Improvements in Valve-Fittings for Soda - Water Apparatus, of which the following is such a full, clear, and exact description as will enable any one 10 skilled in the art to which it appertains to make and use the same, reference being had to the accompanying drawings, forming part of this specification.

The principal objects of my present invention are to provide a soda water fountain valve-fitting having but a single hand-valve controlling the passage through which the water and charging gas are introduced and the charged water withdrawn, and which 20 fitting at the same time permits both charging and discharging of the cylinder without removing the fitting, thereby avoiding the necessity of removing the valve fitting to charge the cylinder, as has heretofore been 25 the general practice, the drawback to this frequent removal of the valve-fitting being the rupturing of the joint between the block-tin lining of the fountain and the bung or pipe-connection to which the valve-fitting 30 is connected.

With these and other objects in view, my invention consists in the various novel and peculiar arrangements and combinations of the several different parts of the apparatus, 35 all as hereinafter fully set forth and then pointed out in the claims.

I have illustrated types of my invention in the accompanying drawings, wherein;—.

Figure 1 is a longitudinal vertical section 40 view of a soda water fountain or cylinder shown as having my improved fitting applied thereto. Figs. 2 and 3 show, respectively, enlarged views of vertical central sections of the fitting shown as detached, the 45 sections being taken at right angles to each other, in these two views. Fig. 4 is a view of a central longitudinal section of a modified form of the fitting.

Referring to the drawings, in which like 50 numbers of reference designate like parts throughout, 1 is a soda fountain consisting in a cylinder made of suitable metal to withstand the internal pressure from the con-

tents thereof and which is provided upon its interior with a continuous lining 2 made of 55 block tin. At the upper end of the cylinder is a perforation 3 through which extends a pipe section or nozzle 4 which is provided with an interior screw thread. Upon the inner end of the pipe section 4 is an annular 60 flange 5 which fits snugly in between the cylinder 1 and the lining 2 and to which the lining is secured in order to form a gas and water tight joint. The exterior of the outer end of the nozzle is provided with a screw 65 thread on which works a nut 6 for drawing the nozzle upwardly and securely locking it in place in the cylinder. The fitting comprises a valve casing 7 provided with a valve chamber 8 in which works a valve 9 which 70 is made of suitable soft material and seats itself on the annular ridge 10 which is rounded as indicated to prevent cutting the soft material of the valve. The valve is provided with a stem 11 which has a screw-thread 12 working in a corresponding screw-thread upon the interior of the removable part 12^a which at its inner end has an external thread 13 fitting a corresponding internal thread in the tubular extension 14. A 75 washer 15 is placed between the part 12^a and the end of the tubular extension 14 to make a gas and water tight joint and the outer end of the valve-stem 11 passes through a removable cap 16 which has an interior screw-thread 17 fitting a corresponding exterior thread on the outer end of the removable part 12^a, and a soft washer or packing 18 is placed within the cap, as indicated, to make 80 the joint gas and water tight. The valve 90 casing has a branch 19 through which extends a passage 20 communicating with the lower end of said branch and with the valve-chamber 8, the valve-seat 10 being at the inner end of this passage 20. The exterior of 95 the branch 19 is screw-threaded at 21 to fit the internal screw-thread of the pipe-section or nozzle 4, and it is also provided with a lateral flange 22 in the under face of which is sunk a soft annular washer 23 which bears 100 down against the upper end of the pipe-section 4 when the fitting is screwed down hard and thus provides a gas and water tight joint between the fitting and the pipe-section 4. To the lower end of the branch 19 of the fitting is soldered or suitably secured the tube 105

24 which is used for both filling the cylinder and withdrawing the contents, and this pipe extends to near the bottom of the cylinder, as indicated in Fig. 1. The fitting 7 is also 5 provided with another lateral branch or extension 25 through which extends a passage 26 communicating with the valve-chamber 8 so that this valve controls the communication between the passage 20 and the passage 26. This branch part 25 is provided with an 10 external screw-thread 27 by means of which it may be coupled with any device for withdrawing the contents of the cylinder or with the pipe for charging the water within the cylinder with carbonic acid gas. If it be 15 attempted to fill the cylinder with liquid, by opening the valve 9 and forcing the liquid in, it will be found that the necessary quantity of liquid cannot thus be forced in, with- 20 out some means of venting or permitting a quantity of the contained air to escape. For this reason it has been the custom to remove the fitting in order to obtain the large opening provided through the pipe-section 4 and 25 to then fill the cylinder by a pipe or hose inserted in the nozzle and to the desired height, though, of course, these cylinders are not entirely filled with liquid as some considerable space must be left for the compressed gas 30 with which the water is charged.

In my present invention, I provide an air vent which comprises a duct or passage 29 extending through the fitting and communicating at its lower end with the short tube 30 which runs down parallel with the main tube 24 and is soldered thereto at 31. The outer end of the air duct 29 extends through a boss or projection 32 which is provided with a hand valve comprising a cap 33 hav- 35 ing an interior screw-thread 34 working on a corresponding screw-thread 35 on the boss or extension 32, and this cap is provided with a lateral opening 36. The air vent 29 opens upon the outer end of the boss or ex- 40 tension 32 which forms practically a valve-seat for the valve 37 which is made of soft material and this closes by screwing down the cap tight upon the boss, as shown in Fig. 4. This cap 33 is provided on its exterior 45 with flat faces 38 like those of a nut for receiving a wrench to turn down the valve hard to close it and to loosen the same when it is desired to vent the cylinder, the vent 29 being in free communication with the 50 lateral perforation 36 in the cap when the cap is partly unscrewed, as shown in Figs. 2 and 3. In order to prevent the cap from becoming detached, I provide the same with an inwardly projecting pin 39 which takes 55 into an oblique slot 40 in the side of the boss 32, and this pin and slot serve to retain the cap from detachment, as will be readily understood from the drawings.

In Fig. 4, I show another form of the 60 fitting, it being substantially the same as that

described in the other figures with the exception that instead of the air vent 29 opening through a boss upon the upper end of the fitting, it opens into a socket 41 in the side of the fitting which socket or cavity is provided with an internal thread for receiving the exterior screw-thread 42 on a plug 43, and this plug is provided with an L-shaped 70 passage 44 extending longitudinally into the same and then laterally so as to open on one side of the plug as well as the end, as indicated in Fig. 4. This plug is provided with a lateral flange 45 beneath which is a washer 46 for bearing upon the outer end of the socketed part 47. This washer 46 and the 75 end of the socketed part 47 form practically a valve and its seat, so that the vent may be closed by screwing the plug in tight, in which case the vent 44 opening upon the side of the plug will be completely covered and 80 closed air and water tight. By unscrewing this plug partially or entirely the vent may be opened. The outer end of this plug is provided with flat faces for receiving a wrench like the part 38 of the valve cap 33 85 in the other construction.

The upper end of the fitting 7 in Fig. 4 is provided with a rounded projection 50 which like the end of the valve cap 33 in the other figure, may be used as a handle in 90 rolling the cylinder 1 on its lower end from place to place, the same as a barrel is rolled by a person in moving it from one point to another.

It will now be understood that with this 100 venting arrangement, the cylinder may be filled with water to the required height without removing the fitting at all, so that the same becomes practically a permanent fixture of the soda fountain or cylinder. In 105 charging these fountains, it is the practice to only partially fill the vessel in order to leave above the water therein a space for the charging or carbonating gas which is also injected into the fountain. The length of 110 the vent-pipe 30 depends somewhat upon the amount of liquid with which the cylinder is to be charged so that where a less quantity of water is to be used the vent-pipe 30 is made longer than when the cylinder is to be 115 charged with more water. Accordingly if desired, this vent-pipe 30 may be varied in length depending upon whether the cylinder is to contain a less or greater amount of water. By attaching a pipe, such as 48, to 120 the lateral branch 25, the empty cylinder may have the water forced therein to fill it, by opening the valve 9 by means of the handle 49 secured to the end of the valve stem 11 at the same time opening the valve 125 of the vent passage 29. Under this condition, as the water is forced in the cylinder, it begins to compress the air above the water, as the water enters much more rapidly than the air can escape through such a small 130

passage as 29. When the water rises in the filling operation to a point above the lower end of the vent pipe 30, the pressure of the air above the water will begin to force the water up through the vent pipe and this will continue until a quantity of water is forced out of the outer end of the air vent 29, so as to be seen by the operator, and this indicates that it is time to shut off the supply of water 10 as the same has then reached the required height in the cylinder. In this way the venting arrangement also serves as a gage for informing the operator as to the quantity of water in the cylinder and letting him 15 know when to stop the filling process. Ordinarily, the proper height of the water is ascertained in filling these cylinders with the fitting removed by the operator inserting a stick or rod in the nozzle 4 and withdrawing it to note the height of the water in the cylinder.

It will, of course, be understood that the outlet or ejection port of the air vent may be located upon any part of the valve casing, I having herewith shown two such locations both of which provide very convenient arrangements. Of course, any well-known form of hand valve may be used to control the venting part.

Having thus described my invention what I claim and desire to secure by Letters Patent is:

1. In a soda water apparatus the combination of a cylinder provided with a nozzle, a fitting adapted to be detachably secured to said nozzle and comprising a valve casing provided with a valve chamber having a valve seat located therein, two oppositely projecting horizontal extensions on said valve casing and a downwardly projecting extension adapted to fit said nozzle, a hand-operated valve closing on said valve seat and provided with a stem having a bearing in one of said oppositely projecting horizontal extensions of the valve casing and controlling the passage for liquid, a passage for liquid extending through the said downwardly projecting extension to the valve seat and from the valve chamber thence through the horizontal extension opposite that in which the valve stem is mounted and said lateral extension adapted to be connected with a pipe or the like, an air vent extending from a suitable point in said cylinder through the said downwardly projecting extension and the valve casing to an exterior point thereon, and provided with a hand valve, substantially as and for the purpose set forth.

2. In a soda water apparatus the combination of a cylinder provided with a nozzle, a fitting adapted to be detachably secured to said nozzle and comprising a valve casing provided with a downwardly projecting extension adapted to fit said nozzle and with

two horizontally extending extensions, a valve chamber within said casing and a valve seat located therein, a hand operated valve closing on said valve seat and provided with a valve stem mounted in one of said horizontal extensions and controlling the passage for liquid, a passage for liquid extending through said downwardly projecting extension to the valve seat and a similar passage extending from said valve chamber through the other said horizontal extension and said lateral extension adapted to be connected with a pipe or the like, whereby said valve controls the flow of liquid into and from said cylinder, an air vent extending from a point a considerable distance within said cylinder through said downwardly projecting extension and valve casing to an exterior point thereon, and a hand operated valve cap for controlling the said air vent, the said air vent serving to both permit the filling of the cylinder without removal of the valve fitting and to gage the height to which the cylinder can be filled with liquid, substantially as and for the purpose set forth.

3. In a soda water apparatus, the combination of a cylinder provided with a nozzle, a fitting adapted to be detachably secured to said nozzle and comprising a valve casing provided with a downwardly projecting extension 19 formed with a passage 20 and adapted to fit said nozzle, oppositely projecting horizontal extensions 25 and 14, the former being provided with a passage 26, a valve-chamber 8 formed within the casing and provided with a valve-seat 10, the tubular part 12^a mounted upon said extension 14 and a valve-stem 11 mounted in said tubular part 12^a and provided with a valve 9, a boss 32 mounted on the valve-casing, an air-vent 29 extending through said fitting and terminating at its outer end on the upper end of the boss 32, an air-pipe 30 connected with said air-passage 29, the said boss 32 being provided with a screw thread 35, and a valve-cap 33 provided with a screw-thread engaging the thread 35 of the boss, substantially as and for the purpose set forth.

4. In a soda water apparatus, the combination of a cylinder provided with a nozzle, a fitting adapted to be removably attached to said nozzle and comprising a valve-casing having a valve-chamber and provided with two oppositely projecting extensions, and with a third extension projecting at right angles to the other two said extensions and adapted to fit the nozzle, a valve-seat within said valve-chamber and a passage leading from said valve-seat through the said third extension, a valve closing on said valve-seat and provided with a valve-stem mounted in the other said oppositely projecting extension whereby the said valve controls communication between said passages, an air-

vent extending through said fitting and provided at its outer end with a hand operated valve comprising a screw-cap controlling said outer end of the vent, and a vent-pipe 5 connected with the inner end of said air-vent and extending to a suitable point within said cylinder, substantially as and for the purpose set forth.

In testimony whereof, I have hereunto set my hand in the presence of the two subscribing witnesses. 10
